Int. Cl. D11—02

U.S. Cl. D35—3 R

FIG. 1

FIG. 2

FIG. 3

FIG. 1 is a top plan view of a nursery pot showing my new design.

FIG. 2 is a front elevation thereof.

FIG. 3 is a bottom plan view thereof.

The characteristic feature of my design resides in the specific configuration of the nursery pot having vertically extending ribs and an indented base portion.

I claim:

The ornamental design for a nursery pot, substantially as shown and described.
